UNITED STATES PATENT OFFICE.

PHILLIP HIEN, OF ROCK ISLAND, ILLINOIS, ASSIGNOR TO BASIL D. BUFORD AND SARAH HIEN, OF SAME PLACE.

CAR-COUPING.

SPECIFICATION forming part of Letters Patent No. 244,895, dated July 26, 1881.

Application filed March 25, 1880. (No model.)

To all whom it may concern:

Be it known that I, PHILLIP HIEN, a citizen of the United States, residing in Rock Island, Illinois, have invented certain Improvements 5 in Car-Couplings, of which the following is a specification.

My invention relates to sundry improvements, fully described hereinafter, in the car-coupling with a pivoted hook for which Letters Patent No. 190,858 were granted to my assignees Sarah Hien and B. D. Buford, May 15, 1877, one of the objects of my present improvements being the relief of the brakeman or other attendant from the duty of preparing the coupling for the self-locking of the pivoted hook, a duty which is demanded by the said patented coupling and by other couplings of the class to which my invention relates, but which is obviated in my present improvement by causing the pivoted hook in the act of being opened to so adjust the locking device that it will perform its duty of locking the hook when the latter is closed.

A further object of my invention is to avoid the use of springs in connection with the operating parts of the coupling, springs being uncertain in their action and liable to be broken during the rough usage to which all couplings are necessarily subjected.

Another object of my invention is to so cover or inclose the locking device within the coupling-head as to protect it from snow and rain which has hitherto been such a serious objection to couplings of the class to which my invention relates, especially during the winter months.

In the accompanying drawings, Figure 1, Sheet 1, is a plan view, partly in section, of my patented coupling; Fig. 2, plans, partly in section, of my improved coupling as it appears when both pivoted hooks are open; Fig. 3, the same, showing both pivoted hooks closed and interlocked; Fig. 4, a side view of the coupling; Fig. 5, Sheet 2, a perspective view of 45 coupling-head and pivoted hook detached from each other and drawn to an enlarged scale, part of the coupling-head being cut away; Fig. 6, an enlarged sectional view of coupling-head with pivoted hook attached; Fig. 7, a perspective view of the lifting-pin; Figs. 8, 9, 10, 11,

and 12 sectional diagrams illustrative of the device for locking and releasing the pivoted hook; Figs. 13 and 14, diagrams illustrating the action of a modified locking and releasing device; Figs. 15 and 16, Sheet 1, sectional 55 plans, showing modifications of my improved coupling.

I will refer in the first instance to my former patented coupling, shown in Fig. 1, where A represents one of the coupling-heads connected to the body of the car in the usual manner, and to a recess in this head is pivoted a hook, B. On one side of the coupling-head is a spring-arm, f, which carries at its end a block, i, adapted to a recess in the hook B. In the act of coupling the pivoted hooks of two draw-heads are interlocked, and the block i is forced by its spring into the recess of the hook, so that the latter will be retained in the position shown in Fig. 1.

The spring-arm is connected by a chain to a lever projecting above the platform, and there is a notch in the hand-rail of the platform for retaining this lever in the position to which it has been moved in unlocking the pivoted hook.

The manipulations required in my former patent are as follows: First, in uncoupling the attendant must so manipulate the lever as to withdraw the block i, the lever being retained by the above-mentioned notch, so that the spring f may be prevented from restoring the block to the recess; second, prior to coupling the attendant must be at hand to move the lever from its retaining-notch and permit the spring to force the block to its place so as to 85 lock the pivoted hook.

One of the objects of my present invention is to relieve the attendant from the latter duty by the device substantially as described hereinafter, so that the pivoted hook cannot be 90 opened in uncoupling without setting the locking device for the performance of its duty in coupling.

The construction of my improved coupling may be best explained by referring to the enlarged perspective view, Fig. 5, and the enlarged sectional plan, Fig. 6.

A portion of the pivoted hook B, which, excepting in the features described hereinafter, is the same as in my said patent, fits freely in 100

a recess in the coupling-head A and is pivoted to the same by a pin, *a*. A locking-block, D, is free to slide vertically in ways in the coupling-head, and this block can be raised by elevating a pin, G, which slides freely through the coupling-head, and which is provided with a projection to act on the under side of the block. When this block is depressed it resists all attempts to open the pivoted hook and move it outward, the block retaining the said hook in the position shown in Fig. 3, for the hook is provided with a projection, *e*, which bears against the locking-block. When the latter is elevated, however, beyond the range of the said projection *e* the hook is at liberty to open in uncoupling, as shown in Fig. 2. It will be seen that this locking-block D performs the same functions as the block *i* in my former patent, and that the same manipulation would be required in attending to the coupling as that explained above in the absence of the automatic mechanism, which I will now proceed to describe.

Within the coupling-head is an angular pocket, *d*, and in the latter is a loose dog, *x*, the lower end of which bears on the bottom of the pocket. The upper end of the dog being the heaviest it has a tendency to be self-tilting against the inclined side of the pocket and to lean with its nose toward the locking-block, so that when the latter is elevated the dog will fall forward with its nose beneath the said block and will retain the latter in its elevated position; but when the pivoted hook is moved outward in uncoupling its projection *e* will come in contact with the dog, tilt the latter backward in the pocket and release the block, which will fall onto the above-mentioned projection *e* of the hook, and there it will remain until the said projection *e* is moved away from the block, when the latter will fall so as to lock the hook in the position shown in Fig. 3.

It will be seen that by the above-described combination in a coupling of the pivoted hook—a locking block and dog—the said hook cannot be opened in uncoupling without setting the block in a condition to automatically perform its locking duty when that duty is demanded in coupling, and hence that the only manipulation required is the simple lifting of the block in order to uncouple.

A more complete understanding of the action of the locking block and dog in obedience to the movement of the pivoted hook may be imparted by referring to the diagrams, Figs. 8 to 12 inclusive. In Fig. 8 the locking-block is elevated, having been raised by means of the pin G, which, after performing this duty, is permitted to fall, while the block is supported by the dog *x*. On moving the hook outward in uncoupling, the projection *e* of the said hook will tilt the dog back, as shown in Fig. 9, until it is free from the block, when the latter will fall onto the said projection *e*, as in Fig. 10, where the bottom of said block is below the nose of the dog. As the hook swings inward,

in coupling, the projection *e* is withdrawn from beneath the block, and the latter, being free from the control of the dog, will fall and lock the pivoted hook, as in Fig. 11, and here it will remain until the block is again elevated by raising the pin G, as in Fig. 12.

The dog, instead of being contained in a pocket in the coupling-head, may be carried by the pivoted hook, as shown in Figs. 13 and 14, the operation and results being precisely the same as those described above, for when the pivoted hook B is moved inward the dog will be in a position for its nose to support the block when the latter is raised, and on opening the hook in uncoupling it will carry the dog away from the block and the latter will fall onto the projection *e* of the hook preparatory to falling still farther when the hook is closed. This modification is also shown in Fig. 16, 85 Sheet 1.

While different devices—a spring-catch, for instance—for performing the same functions as the dog will readily suggest themselves to an expert mechanic, the dog is to be preferred as it performs its duty by gravity and obviates the necessity of using springs, which are always objectionable in couplings.

The block slides in a box-like projection or cover, *h*, cast on the coupling-head—an important feature of this part of my invention, for the cover at all times prevents the access to the interior of the coupling-head of snow and rain, which have proved to be a serious obstacle to the success of couplings of the class to which my invention relates, especially in the winter months, when the freezing of water which has found access to the coupling-head necessarily interferes with the operating parts. The projection *e* is not so thick as that portion of the pivoted hook which enters the coupling-head, but it may be of the same thickness, in which case a higher cover, *h*, would be required for a block, which must necessarily be raised higher than when the projection is reduced in thickness, as shown; hence I prefer this reduction.

The object of the peculiarly-constructed pin G is as follows: Wherever a lifting-pin is placed there must necessarily be an opening in the coupling-head to receive it, and should a pin be attached to the top of the block and pass through the cover *h*, as shown in Fig. 11, the rain would enter the opening; hence I lift the dog from below by a projection on a pin, G, which pin passes through the coupling-head, preferably at a point where the latter is solid, so that water cannot gain access to the interior of the said coupling-head.

In the modification shown in Fig. 15 the dog occupies a position in a pocket at the back of the block, instead of at one side of the same, an arrangement which demands a protuberance, *m*, of less prominence on the coupling-head than in the plans previously described.

It is not essential that the locking-block and dog should be in the precise position shown,

for the block may be situated at any point where it can be interposed between the back of the pivoted hook and the coupling-head.

I claim as my invention—

5 1. A coupling in which are combined the following elements, namely: first, a coupling-hook pivoted to the coupling-head; second, a block for locking and releasing the hook, and, third, devices whereby the hook, on being 10 opened, is caused to set the block for the automatic locking of the hook when the latter is closed, all substantially as and for the purpose set forth.

15 2. The combination of the coupling-head, pivoted hook, and locking-block with a dog, x ; adapted to a recess in the said coupling-head or in the pivoted hook, substantially as described, so as to admit of being tilted and so as to fall by its own gravity, as set forth.

20 3. The combination of the pivoted hook, locking-block, and dog with a coupling-head

having covered recesses for the reception of the said block and dog, substantially as specified.

4. The combination of the pivoted hook, its 25 projection e less in thickness than that part of the said hook which enters the coupling-head, with the locking-block D and dog x , substantially as described.

5. The combination of the coupling-head, 30 pivoted hook, and locking-block with a lifting-pin, passing through the coupling-head and having a projection whereby the block will be lifted on raising the said pin, all substantially as specified.

In testimony whereof I have signed my name to this specification in the presence of two subscribing witnesses.

PHILLIP HIEN.
